UNITED STATES PATENT OFFICE.

THOMAS E. MCNEILL, OF PHILADELPHIA, PENNSYLVANIA.

IMPROVEMENT IN SEATS AND COUCHES FOR RAILWAY-CARS.

Specification forming part of Letters Patent No. 24,225, dated May 31, 1859.

To all whom it may concern:

Be it known that I, THOS. E. MCNEILL, of the city and county of Philadelphia, and State of Pennsylvania, have invented certain new and useful Improvements in Seats and Couches for Sleeping-Cars; and I do hereby declare the following to be a full, clear, and exact description of the same, reference being had to the accompanying drawings, and to the letters of reference marked thereon.

My invention relates to improvements in sleeping-cars in which the space used as a central passage during the day is occupied for couches at night, and in which the bases and backs of the seats are converted into couches by placing them end to end; and my improvements consist, first, in constructing the end frame of each seat with a slot at the top, and in attaching to the side of the car a plate with a slot corresponding to that in the end frame, so that the slots may receive pins or bolts projecting from the opposite ends of the back of the seat and allow the latter to be reversed at pleasure, as well as to be readily removed, so as to form part of a couch for night use, and this without disturbing the end frame; second, in certain arms hinged to the inside of the end frames, so as to be depressed under the seat during the day and raised during the night, so as to serve as supporters for the central couches; third, in certain frames hinged to the side of the car, so as to be out of the way during the day and so as to support couches during the night; fourth, in a peculiar manner of hanging a supplementary couch to the roof, so that it may be readily elevated and lowered.

In order to enable others to make and use my invention, I will now proceed to describe the manner in which I carry it into effect.

On reference to the accompanying drawings, which form a part of this specification, Figure 1 is a longitudinal section of sufficient of a railway-car to illustrate my improved seats and couches, which are shown as arranged for day use; Fig. 2, the same as Fig. 1 with the seats converted into couches for night use; Fig. 3, the same as Fig. 2 on the line 3 4; Fig. 5, a plan view of Fig. 1, and Fig. 6 a plan view of Fig. 2.

Similar letters refer to similar parts throughout the several views.

A represents a portion of the floor, B the roof, and C one side, of a railway-car.

D D are the seats, secured permanently to the floor of the car and situated the usual distance apart. When arranged for day use the cushioned board E, which forms the base of the seat, rests at one end on a ledge projecting from the inside of the frame D, and at the opposite end on a ledge secured to the side of the car.

The top of each frame has an oblong slot, a, and to the side of the car is secured a plate with an oblong slot corresponding and directly opposite to the slot in the frame.

The cushioned board E, which forms the inclined back of the seat, has on each end a pin or bolt, that of one end being adapted to the slot in the plate, which, as before remarked, is secured to the side of the car, and that on the opposite or outer end of the back being adapted to the slot in the top of the frame D. The slots both in the plate and the frame have recesses in each end in which the pin or bolt may rest steadily until the back is purposely moved from one side of the seat to the other. To whichever side of the seat the back may be moved it will be effectually supported in its inclined position by the pins resting in the recesses of the slots in the plate and frame, and by the lower edge of the back resting on the cushioned boards E of the seat.

The above arrangement affords an opportunity for the disposal of the two rows of seats in the car in a manner precisely similar to that of ordinary cars, the seats as regards the reversing of the backs being equally as convenient as common seats, while they admit of being readily converted into reclining-couches in the following manner:

It will be observed that on the inside of each frame D is hinged an arm, which, during the day, is bent down so as to be under the base F of the seat, and therefore out of the way.

When the seats have to be converted into couches the arms d are raised, as best observed in Figs. 3 and 4. The bases F of two adjacent seats are removed from their ledges and placed end to end in the space between the two rows of seats, as seen in Fig. 6, the boards resting on the tops of the upturned arms d, which are furnished with projections fitting into staples on the boards, which are thus retained firmly in a proper position, and form a steady couch

for reclining purposes. The backs F of the seats, which should be removed prior to the base E, are also placed end to end between the two rows of seats, and are deposited on ledges projecting from the outside of the frames D. (See Fig. 4.) The backs and bases of two adjacent seats thus form two couches for sleeping purposes. The bases and backs of the two seats opposite to those which have been thus converted into couches are disposed of as follows: The two backs are placed end to end and situated on one side of the car, and the two bases placed end to end and situated on the opposite side of the car, so as to form a couch on each side. One of these couches is represented at M, Fig. 4, and rests in the middle on a strip, e, secured to the floor, and at the opposite ends on ledges on the frames N, which are hinged to the side of the car, so as to be folded back during the day and moved out at night. These frames carry another couch, P, which is situated immediately above the couch M, and above the couch P a third couch is suspended to hangers m, secured to the roof of the car.

The two couches P and Q consist of cushioned boards, which, during the day, may be hoisted up to the roof and there retained by turn-buckles or other suitable devices. Another cushioned board, R, forms another couch, and is hung to the roof, of the car in a peculiar manner immediately above the space which forms the passage between the two rows of seats as arranged for day use.

The hangers n, which support the couch R, are hinged to the roof, instead of being stationary, and are confined to the boards by a longitudinal bar, p, which serves to keep the board in its proper position when down, and when the latter is raised the bar serves as a guide, carrying the hangers up to the roof of the car, as seen in Fig. 1, where the whole is confined by any suitable devices.

It should be understood that the bars or bolts

in each end of the backs F of the seat are so connected to the latter that they may be pressed into a recess so as to yield and allow two of the backs to be brought close together when placed end to end. The bolts, however, are projected outward by means of springs when the backs are removed from the position they occupy as couches.

It will now be seen, without further description, that by the above-described arrangement of seats and couches the usual accommodations are afforded for passengers during the day, and more than the requisite number of couches during the night, the arrangement at the same time admitting of the usual central passage through the car during the day and affording two passages during the night.

I claim and desire to secure by Letters Patent—

1. The end frame, D, of the seat, with its slotted top and the slotted plate secured to the side of the car, in combination with the back F and its pins or bolts, when the several parts are adapted to and arranged in respect to each other substantially as set forth.

2. The arms d, so hinged to the inside of the end frame as to be folded down under the seat during the day and elevated so as to form supports for the couches during the night, in the manner specified.

3. The vertical frames N, hinged to the side of the car and furnished with ledges to support two couches.

4. The board R, its rods p, and the hangers n, when arranged as and for the purpose herein set forth.

In testimony whereof I have signed my name to this specification in the presence of two subscribing witnesses.

THOS. E. McNEILL.
